UNITED STATES PATENT OFFICE.

RALPH E. SMITH, OF GALION, OHIO, ASSIGNOR TO THE GALION METALLIC VAULT COMPANY, OF GALION, OHIO, A CORPORATION OF OHIO.

GRAVE-VAULT HANDLE.

Application filed March 31, 1927. Serial No. 180,017.

My invention relates to handles, and in particular to a handle for a grave vault.

It is the object of my invention to provide a base handle for vaults which is cheap to manufacture, strong, and can be electrically welded over a malleable handle.

It is a further object of my invention to provide means of securing the two parts together, which does away with welding or riveting.

It is a further object of my invention to provide embossed studs in connection therewith so that the vault may be easily moved upon the floor or platform, which facilitates further the loading of the vault into cars.

Referring to the drawings:

Figure 1 is a perspective of a portion of the grave vault base with the handle in position;

Figure 2 is a top plan view of the handle partially in section;

Figure 3 is a rear elevation of one end of the handle;

Figure 4 is a section on the line 4—4 of Figure 2 looking in the direction of the arrows.

Referring to the drawings in detail, 1 is an attaching plate having a struck-up portion 2 that forms a projecting stud upon which the bottom of the vault 3 may rest.

This attaching plate 1 is provided with a pair of spaced outwardly extending arms 4 terminating in a T-head 5. The base 1, arms 4 and T-head 5 are integral and may be made of very heavy steel adapted to be formed in relatively rough condition to provide great strength without the necessity of a fine finish as the parts are not seen by the observer. In order to provide a decorative handle, I form over the arms 4 and T-head 5 from a single thin finished sheet of metal a suitable handle, which will not only have the proper appearance and decorative value by reason of its form and finish, but will also provide an adequate comfortable hand hold for the person engaged in carrying the vault, to which the handle is attached.

This one-piece formed handle consists of an outside plate 6 having side walls 7 formed thereon to compose the top, bottom and ends of the handle to give the handle a neat appearance and finish.

A portion of these side walls centrally between the T-heads 1 are formed into a rear wall 8 providing a closed tubular body

around which the operator's hand may be placed without injury by any rough edge. The T-heads 5 fit between the side walls 7 behind the front walls 6 and one end thereof projects slightly into the tubular portion 60 formed by the rear walls 8. The plate 6 is provided with depending members 9 which are wrapped around the arms attaching the decorative handle to the supports by this means.

These enclosing or enwrapping portions are designated 10.

Thus, the upward lift is taken on the T-head 5 and the handle itself is attached by the members 10.

Thus, with a very simple construction of two pieces without the necessity of any welding, bolting, or the like, I am enabled to provide a very strong, and, at the same time, decorative handle, utilizing the rough integral steel plate of great strength for the attaching means and the relatively thin formed metal covering for the handle means.

It will be noted that the T-head is provided with arcuate surfaces 11 where the T-head engages with the head 4.

The handle is similarly formed as at 12 to engage with this arcuate portion of the T-head and the under side of the T-head in order to form a more extended surface.

It will be further apparent that it is possible to form the handle, with the exception of the parts 10, mounted upon supports and then by a simple operation in the brace or a hammer, forming the parts 10 around the 90 arms 4.

It will be further understood that I desire to comprehend within my invention such modifications as may be necessary to adapt it to varying conditions and uses.

Having thus fully described my invention, what I claim as new and desire to secure by Letters Patent, is:

1. In combination, an attaching plate having a depressed portion for use as a supporting stud, outwardly extending arms, and cross heads, a relatively thin metal plate formed on said arms and cross heads embracing said arms, the intermediate portion of said handle being formed into a tubular portion for the hand of the person grasping the handle.

2. In a grave vault handle, the combination of a flat attaching plate adapted to be welded to the grave vault having depressed

supporting stud arms formed on said plate at an angle thereto having cross heads, and a relatively thin plate formed into a hollow handle around said cross heads and completely around said arms, said portion of the handle between the arms and cross heads being formed into a handle portion approxi-

mately circular in section to receive the hand of the person grasping the handle, while the ends of said handle are formed into front, and side walls only save where wrapped around the arms.

In testimony whereof, I affix my signature.

RALPH E. SMITH.
